END STANDARD FOR A CHAIR OR SIMILAR ARTICLE

Edward W. Harman, Newton, N.C., assignor to Dresden
Lounge Co. Inc., Maiden, N.C., a corporation of North Carolina

Filed Apr. 14, 1969, Ser. No. 16,714

Term of patent 14 years

Int. Cl. D6—01

U.S. Cl. D15—8

FIG. 1 is a perspective view of an end standard for a chair or similar article showing my new design.

FIG. 2 is a perspective view of the opposite face.

FIG. 3 is a cross-sectional view enlarged taken along line 3—3 in FIG. 2.

I claim:

The ornamental design for an end standard for a chair or similar article, as shown.
